flector L is slipped over the body of the lamp and rests on a bead f, and the spring wire is hooked into two holes k' in the reflector, while the loop k engages the lower part of the 5 globe or of the outer one of two globes. In the case where two globes I, I' are used, the top of the wire loop k springs into a depression at the bottom of the outer globe I', and the outer globe supports the inner globe I by 10 means of a perforated metal gallery M, the whole being pressed hard against the body of the lamp by means of the spring. When a single globe I is used, the top of the loop k partially enters the hole in the bottom of the 15 said globe I. The secondary air supply enters beneath the reflector L, passes down between the two globes I and I' and enters the bottom of the inner globe I.

In the construction shown in Fig. 3 in 20 which the heater A is used for poor gases, for instance, Mond gas or Dowson gas, or any other gas of low calorific value, we perforate the nozzle at a^{10} , so as to burn a portion of the mixture of gas and air underneath the 25 lower part of the heater, in addition to what is burned inside the mantle, to intensify the regenerative effect.

In the modified construction shown in 30 Figs. 4 and 4^a the gauze disk B' is dispensed with and a rod S of star section is arranged centrally of the nozzle B, the top of which rod is secured to the central diaphragm A' of the heater. In this way a certain amount of 35 heat is transferred to the diaphragm, which is naturally considerably cooler than the inside of the heater on account of its being met directly by the cool mixture.

I claim:

1. In an inverted incandescent gas lamp, 40 the combination with the burner tube, of a gas and air heater connected to said tube, and a nozzle connected to said heater, said nozzle including a heavy body of metal and a surface of contact for the mantle of non- 45 conducting material, as and for the purpose specified.

2. In an inverted incandescent gas lamp, 50 the combination with the burner tube of a gas and air heater connected to said tube, said heater comprising two cones disposed base to base and a diaphragm perforated at

its edges fixed between said bases, and a nozzle connected to said heater.

3. In an inverted incandescent gas lamp, 55 the combination with the burner tube of a gas and air heater connected to said tube, said heater comprising two cones disposed base to base and a diaphragm perforated at its edges fixed between said bases, swivel catches for holding said cones together, and 60 a nozzle connected to said heater.

4. In an inverted incandescent gas lamp, 65 the combination with the burner tube, of a gas and air heater connected to said tube, said heater comprising two cones disposed base to base, a thermostat composed of two strips of different metal located within the heater, and a nozzle connected to said heater.

5. In an inverted incandescent gas lamp, 70 the combination with the burner tube of a gas and air heater connected to said tube, said heater comprising two cones disposed base to base and a diaphragm perforated at its edge fixed between said bases, and a perforated nozzle connected to said heater. 75

6. In an inverted incandescent gas lamp, 80 the combination with the burner tube, of a regulating screw entering said tube, said screw having a diameter of approximately the internal diameter of the tube, a gas and air heater connected to the tube, said heater comprising two cones disposed base to base and a diaphragm perforated at its edges fixed between the bases, and a nozzle connected to 85 said heater.

7. In an inverted incandescent gas lamp, 90 the combination with the burner tube of a gas and air heater, said heater comprising two shallow cones disposed base to base a perforated diaphragm fixed between the bases of the cones, a nozzle, a slide mounted between the top of the nozzle and its point of attachment to the heater, and a gauze disk fitted to said slide.

In testimony whereof we have signed our 95 names to this specification in the presence of two subscribing witnesses.
